UNITED STATES PATENT OFFICE.

ALFRED H. NEWPHER, OF CHICAGO, ILLINOIS, ASSIGNOR TO THE ADAMS & WEST-LAKE COMPANY, OF CHICAGO, ILLINOIS, A CORPORATION OF ILLINOIS.

CAR-WINDOW.

1,093,644.

Specification of Letters Patent.

Patented Apr. 21, 1914.

Application filed June 21, 1909. Serial No. 503,387.

To all whom it may concern:

Be it known that I, ALFRED H. NEWPHER, a citizen of the United States, and resident of Chicago, county of Cook, and State of Illinois, have invented certain new and useful Improvements in Car-Windows, of which the following is a specification, and which are illustrated in the accompanying drawings, forming a part thereof.

10 The invention relates particularly to the upper, usually an immovable, sash for railway cars commonly known as the Gothic sash; its object is to provide an improved sash for such windows, and means for more effectually closing the joint between this sash and the upper end of the lower movable sash.

The usual practice has been to set the glass of the Gothic window in a single sash which is permanently attached to the car. When 20 the car is shopped for repairs inconvenience and delay result from work upon this window when thus permanently secured in place, and if a new light of glass is required its insertion is practically the last thing to be 25 done, and as a consequence it is difficult to finish the work neatly. These difficulties are overcome by the use of the device herein shown and described, wherein the glass is carried by an inner sash easily removable from 30 an outer sash which is permanently secured to the car, permitting the inner sash to be taken out of the car when the latter comes into the shop, and to be repaired at a bench and easily replaced when all other work upon 35 the car has been finished.

The invention is embodied in a structure such as is hereinafter described, and as illustrated in the accompanying drawings, in which—

40 Figure 1 is a detail elevation of the outer face of the window; Fig. 2 is a detail section on the line 2—2 of Fig. 1, a part of the outer sheathing of a car being shown; Fig. 3 is a detail section on the line 3—3 of Fig. 45 1, showing a portion of the lower sash; and Figs. 4 and 5 are sectional views on the same plane as Fig. 3, but showing modified forms of construction.

A part of the outer sheathing of a car body is shown at 10, and the upper rail of the lower or movable sash of a car window is shown at 11. The Gothic window comprises an outer sash, generally designated as 12, and an inner sash, generally designated

as 13; the glass 14 being set within the inner 55 sash.

The outer sash is shown as being formed of sheet metal folded upon itself to form hollow bars which are substantially oblong rectangular in cross section, the outer face, 60 however, being offset inwardly adjacent its inner edge to form a rabbet, as shown at 15, to receive a flange of the inner sash. The edges of the sheet of which the bars of the sash are formed may meet or overlap and be 65 secured together by any suitable means, such as brazing. This sash is fitted within the window opening of the car and may be held in place by means of plates 16, 17 and 18 extending along its top and sides and overlapping it and the sheathing of the car, this plate being secured to the car body and the sash being secured to it by means of screws 19, 20, as numerously placed as may be desired. Preferably blocks as 21 are located 70 within the chamber of the sash and preferably secured to its walls by means of solder or brazing, these blocks supplying adequate stock within which to form threaded sockets for the engagement of screws. The inner sash is also shown as made of sheet metal doubled upon itself to form hollow 75 rails, these rails being given suitable configuration in cross-section to provide a seat for the glass and to give such architectural 80 finish as may be preferred. Preferably a sheet is used of sufficient width to provide an outstanding flange 22 to fit within the rabbet 15 of the outer sash, the edges of the sheet forming the outer edge of such flange. 85

The seat for the glass 14 is provided by offsetting inwardly the inner face of the sash bar adjacent its inner edge to form a rabbet 23, and the glass, when seated within this rabbet, is secured by a plate 24 which 90 may take the form, as shown, of a continuous frame and is secured to the sash bar by means of screws, as 25, blocks 26 being preferably placed within the chamber of the bar to provide ample stock within which to form 95 threaded sockets for the screws. The inner sash is secured to the outer one by means of screws 27 setting through the flange 22 and entering suitable blocks, as 28, located within the chamber of the bars of the outer sash. 100

While the outer sash as described is, of course, removable from the body of the car, it may, nevertheless, remain as a permanent 105

2

fixture, permitting the painting of the car body as a whole. The inner sash, however, may be readily removed from the outer sash without marring the paint of the body, 5 which may extend over the retaining plates 16, 17 and 18. With the sash as thus made of two members, there may be employed a filling bar, generally designated by the numeral 29, to close the space between the lower 10 bar of the Gothic sash and the upper bar of the lower sash 11. This filler bar is shown as having an outer member 30 made of a piece of sheet metal folded upon itself to form a stem 31, and a chambered head having 15 an opening along its outer face, that is to say, the face directed toward the lower sash. The stem 31 may be retained between overlapping edge portions 32, 33, of the sheet of which the lower bar of the Gothic 20 sash is formed, and secured by means of screws 34, the inner ends of which enter threaded sockets in blocks 35 located within the chamber of the sash bar. Fitted within the head of the filler bar thus formed 25 is a bar 36, preferably of wood, having a channel along one face registering with the opening in the outer face of the bar. Within this channel is placed a cushion 37 of any suitable material, such as felt or rubber, and 30 this cushion may be covered by a sheet 38 of fabric, such as "plush" or rubber, the edges of this sheet overlapping the top and bottom of the bar 36 and being thus securely clamped. The cushion 37 is of sufficient 35 thickness to project slightly through the opening in the filler bar, in order that it may frictionally engage the lower sash and form therewith a joint which will effectively exclude dust and drafts.

40 In the modification illustrated in Fig. 4, the filler between the two sash is made of a single sheet of metal folded to form a hollow bar 39 substantially oblong rectangular in cross-section. The face of the bar 45 adjacent the movable sash has an inward fold 40, to form a pocket within which is housed a cushion, such as the rubber tub-

ing 41 shown, which projects slightly beyond the face of the bar and bears against the sash rail. The marginal portions of the 50 sheet meet between the top and bottom of the face of the bar adjacent the fixed sash and are bent outwardly to form a stem 42, to be secured between the overlapping marginal portions 32, 33, of the sheet of which 55 the lower cross-bar of the fixed sash is made.

Fig. 5 shows a further modification of the filler bar interposed between the two sash, differing from the form illustrated in Fig. 4 essentially only in that the cushion is attached to the movable sash and frictionally engages the filler bar, instead of being attached to the bar engaging the sash.

I claim as my invention—

1. In a window, in combination, a vertically movable sash, a bar crossing the window opening and coöperating with the upper rail of the sash, such bar being made of sheet metal wrought to the form of a tube, the edges of the sheet being overlapped, a 70 filler bar interposed between the upper rail of the sash and the bar, such filler bar being made of sheet metal folded to form a flange fitting between the overlapping marginal portions of the first-named bar and a chambered head having a longitudinal opening, and a cushion housed within the head and projecting through its opening and adapted to bear against the upper rail of the sash.

2. In a window, in combination, a sash 80 made of sheet metal wrought to the form of a tube, the edges of the sheet being overlapped, a filler bar for frictionally engaging an adjacent sash, such bar being made of sheet metal folded to form a flange fitting 85 between the overlapping marginal portions of the first-named sheet, and a chambered head having a longitudinal channel, and a cushion housed within the channel and projecting beyond the side face of the head.

ALFRED H. NEWPHER.
